UNITED STATES PATENT OFFICE.

CHARLES A. PARKER, OF HAUGAN, MONTANA, ASSIGNOR OF ONE-HALF TO GEORGE R. WELLS, OF DEBORGLIA, MONTANA.

TIMER.

Application filed November 5, 1926. Serial No. 146,326.

My present invention relates to improvements in timers of the commutator type for ignition systems of internal combustion engines, in which a rotor or brush-holder is 5 revolved at a predetermined speed ratio from the engine shaft, with relation to a stator, for causing successive makes and breaks in proper order of electrical circuits controlling the ignition devices. 10 The primary object of the invention is the provision of a compactly arranged device that is comparatively inexpensive in cost of production, simple in construction and operation and highly efficient in the performance 15 of its functions of distributing the electrical currents as required.

By the utilization of the device of my invention, a maximum friction surface is provided between the moving and stationary 20 contact members; uniformity in wear on the operating parts is insured; a reliable and close frictional contact is maintained, and compensation is made for wear of parts, thus prolonging the durability of the timer.

The invention consists in certain novel 25 features of construction involving the rotor and stator, and combinations and arrangements of elements embodied in these parts as will be specifically pointed out and 30 claimed.

In the accompanying drawings I have 35 illustrated a single brush-holder and a duplex brush-holder in two complete examples of the physical embodiment of my invention wherein the parts are combined and arranged according to the best modes I have 40 thus far devised for the practical application of the principles of my invention.

While I have shown the invention as 45 adapted for use in connection with a four-cylinder engine, it will be apparent that the timer may readily be converted for use in connection with other types of engines without departing from the spirit of my invention.

Fig. 1 is a sectional view of the timer embodying a duplex brush-holder.

Figure 2 is a transverse sectional view at line 2-2 of Figure 1.

Figure 3 is a reduced exterior side view of the timer.

Figure 4 is an enlarged sectional view of the timer with the parts separated.

Figure 5 is an enlarged perspective view

of a portion of the timer showing the insulating ring, a stationary contact member thereon, and one of the terminal lugs. 55

Figure 6 is a face view of one of the brush-holders.

Figure 7 is a sectional view of the timer, 60 using a single brush-holder.

Figure 8 is a transverse sectional view of Figure 7.

Figure 9 is a perspective view of the brush-holder. 65

Figure 10 is a sectional view showing the parts of the timer separated.

Figure 11 is a perspective detail view showing one of the stationary contact members and its connections. 70

In carrying out my invention I utilize the rotary shaft 1 which may be a crank shaft of an internal combustion engine, and the shaft is supported in suitable bearings and in a portion of the crank case 2. As shown 75 in the drawings, the shaft projects through the crank case wall and the end of the shaft in Figure 1 is provided with a pair of hubs 3 and 4 forming part of the duplex brush-holders or rotor of the timer. These hubs are carried by the shaft and they are locked together with a clutch device indicated as 3' and 4' in Figure 1, and a locking nut 5 on the end of the shaft provides a rigid structure for rotation with the shaft 1. 80

Each of these hubs is provided with a crank arm, as 6 and 7, and each of these arms at its outer end, supports a rectangular spring frame as 6' and 7'. These rectangular frames straddle the hubs on the shaft, 85 and form the holders for the triangular shaped brush heads 8 secured at the free ends of the frames. In Figure 1 it will be seen that the crank arms 6 and 7 are parallel with each other, and the resilient rectangular frames 6' and 7' are aligned and arranged in complementary manner. As best seen in Figure 6 the brush heads 8 are riveted to the free ends of these resilient 90 holders. The brush heads which are preferably made of copper or phosphor bronze are fashioned in a wedge-shape or of triangular shape in order that their side edges may make an easy and smooth contact with the stationary contact members as the 95 brushes rotate with their holders.

The duplex brush-holders rotate or revolve in a housing which may be made up

of insulating material, as Bakelite, and the base ring 9 of the housing is fitted in the counter-sunk outer face of the crank case 2. The cap 10 of the housing which is also shown as constructed of insulating material is secured on the base ring 9 by means of the usual retaining spring 11.

Within the housing are contained the stationary contact members 12, here shown as four in number. These contact members are made up in U-shapes, and each contact member has an integral perforated terminal lug 13 for the lead wires indicated as 14 and 15 in Figure 1. The stationary contact members are secured to a non-conducting ring 16, which is made up of fiber or other insulating material. The insulating ring 16 is grooved and counter-sunk to accommodate the U-shaped contact members, and it will be apparent that these stationary contact members on opposite sides of the insulating ring are adapted for use with the duplex brush heads 8 which are adapted to revolve in planes at opposite sides of the insulating ring.

The insulating ring is secured in the housing by means of the lugs 13 which project outwardly through complementary notches 17 in the circular edge of the cap 10, and in this manner the stator, or insulating ring and its stationary contact members, is held against movement.

In Figure 7 the cap or housing 18 is secured to the crank case 2 in suitable manner, and a single brush-holder is enclosed within the housing. This brush-holder or rotor comprises the sleeve 19 which is secured on the shaft 1 by means of the nut 5, and the radial arm 20, to which the resilient rectangular frame 21 is secured. This frame straddles the hub 19, and carries the brush head 22. The stator is made up of an insulating ring 22' fashioned of fiber or other suitable material, and is provided with four stationary contact points or members 23.

These members or contacts 23 are arranged on one side only of the insulating ring, and the contacts are fashioned with end flanges 24 to engage the opposite sides or edges of the ring. At 25 the insulating ring is provided with notches for the reception of a bolt head, and the terminal screws 27 extend through the housing 18 from these bolt heads. The lead wires 28 are secured to these terminals by the usual nuts 29.

In Figure 10 the resiliency of the brush-holder will be illustrated, and it will be apparent that when the housing is slipped over the end of the shaft as indicated by dotted lines, the resilient frame 21 will be placed under tension to hold the brush 22 in frictional contact with the stator. Thus as the rotor revolves with the shaft the brush 22 is caused to make successive make and break contact with the stationary members or contacts 23 of the insulating ring 22'.

Having thus fully described my invention what I claim as new and desire to secure by Letters Patent is:

1. In a timer the combination with a stator comprising an insulating ring having complementary U-shaped contacts, of a pair of opposed resilient open frames forming holders and brushes on said holders, a rotary shaft, a pair of hubs on said shaft and a rigid connection therebetween, and a supporting arm on each hub for said holders.
2. In a timer the combination with a stator comprising an insulating ring having complementary U-shaped contacts, of a pair of opposed resilient open frames forming holders and brushes on said holders, a rotary shaft having a threaded end, a pair of hubs on said shaft having complementary clutches tongues and notches, a supporting arm on each hub for said holders, and a lock nut on the shaft.

In testimony whereof I affix my signature.

CHARLES A. PARKER.
